[57] ABSTRACT

[21] Appl. No.: 385,985

A rotary brush assembly is provided having a hub assembly comprising a series of interlocking one-piece hub members arranged end to end on a driven shaft. Each hub member is provided with an integral flange extending outwardly from the outer tubular wall of an annular channel and having a series of circumferentially spaced slots which receive tabs projecting from the channel of the next adjacent hub member. The hub assembly is an extremely valuable improvement because its high quality and great strength are accompanied by a drastic reduction in the cost of manufacture of the brush assembly.

FIG. 5

INTERLOCKING ROTARY BRUSH CONSTRUCTION

The present invention relates to a rotary brush assembly and more particularly to a low-cost high-quality brush assembly having interlocking sheet metal hub members arranged end-to-end to support a series of rotary brushes.

The rotary brush assembly of this invention is an improvement in the type of brushing machinery described in my U.S. Pat. No. 3,643,281 granted Feb. 22, 1972. As pointed out in column 1, lines 24 to 48, of that patent, various other constructions were previously employed as disclosed in Radinse U.S. Pat. No. 3,084,367, my U.S. Pat. No. 3,106,737 and Peterson U.S. Pat. No. 2,316,185.

The present invention involves the discovery of a simple, unique assembly which is much better than any of the above and which provides high quality, strength and durability while greatly reducing the cost of manufacture.

The brush assembly of the present invention employs a series of identical sheet metal hub members which can easily be produced at low cost from a flat metal sheet by simple conventional stamping operations. Each hub member comprises an annular channel and an integral radial flange having a large number of tab-receiving slots. The channel of each hub member is slotted to provide a large number of integral elongated tabs which are adapted to extend through the aforesaid slots of an adjacent hub member when the hub members are arranged end to end in an assembly. A conventional rotary brush with an annular hub ring is mounted on each of said hub members and is held in position between the radial flanges of the hub members, the tabs of each hub member being held in radial positions between the radial flange of the adjacent hub member and the hub ring carried by the latter hub member. The hub ring is upset at circumferentially spaced portions to provide protrusions or lobes which fit corresponding depressions in the hub member to prevent angular movement of the ring on the hub member.

Objects of the invention are to provide a simple, inexpensive rotary brush assembly which can readily be assembled at minimum cost and to provide a strong durable assembly suitable for heavy duty use.

These and other objects, uses and advantages of the present invention will become apparent to those skilled in the art from the following description and claims and from the drawings.

In the drawings:

FIG. 1 is a fragmentary transverse sectional view showing a rotary brush assembly constructed according to the present invention;

FIG. 2 is a fragmentary longitudinal sectional view taken generally along the line 2-2 of FIG. 1 and on a larger scale with portions shown in broken lines;

FIG. 3 is a fragmentary longitudinal sectional view taken substantially on the line 3-3 of FIG. 1 and on a larger scale;

FIG. 4 is an exploded longitudinal sectional view somewhat similar to FIG. 2 but with parts separated to show the method of assembly; and

FIG. 5 is a perspective view of the brush assembly also showing the method of assembly.

Referring more particularly to the drawings, which are drawn substantially to scale and in which like parts

are identified by the same numerals throughout the several views, FIGS. 1 to 5 show a cylindrical rotary brush assembly B constructed accordingly to the invention having a cylindrical shaft or arbor 2, which may be driven at high speed, a large number of circular rotary brushes 3 with long radial bristles 4 supported on channel-shaped hub rings 5, and a corresponding number of annular sheet metal hub members 6 arranged end to end in interlocked relation to provide a rigid hub assembly 7. The shaft 2 has a pair of parallel diametrically opposed keyways 8 extending substantially the full length of the shaft which receive a pair of long metal keys 9 of uniform rectangular cross section, which may also extend the full length of the shaft.

Each rotary brush 3 may be similar to a conventional rotary brush of the type disclosed in U.S. Pat. No. 3,307,213 and may have the bristles 4 firmly secured to the hub ring 5 in the same way with an annular locking ring 11 of U-shaped cross section located in the channel. As herein shown, each ring 5 has an internally cylindrical portion 12 extending axially between identical radial flanges 13 and 14. Each of said flanges is deformed to grip the bristles 4 and has a large number of regularly arranged radial indentations or pleats 15 closely spaced around the circumference. Also, in accordance with the present invention, the ring 5 is deformed by squeezing and upsetting the flanges 13 and 14 to provide the flanges with a series of regularly circumferentially spaced indented portions 16 and to provide the portion 12 of the ring with rounded, bulged or protruding lobes 17. Except for the indented portions 16 and associated lobes 17, each rotary brush 3 may be constructed substantially as disclosed in said U.S. Pat. No. 3,307,213.

The one-piece hub members 6 of the present invention are preferably formed of sheet metal and comprise a flat annular radial flange 19 of uniform radial width integral with an annular channel 20 of uniform radial width. The radial flange has a large number of regularly arranged circumferentially spaced tab-receiving slots 18, which are preferably elongated circumferentially to a length of 0.2 to 0.5 inch or so and are usually spaced apart a distance at least several times the length of each slot (for example, a distance of 1 to 3 inches).

The channel 20 is cut or slotted to provide a large number of elongated integral tabs 21 and a corresponding number of vertically elongated slots 22 of the same size and shape. Each tab 21 is formed in axial alignment with one of the slots 18 and is of a size to fit loosely in the slot, the width of each tab being preferably uniform and slightly less than the length of the slot 18. The tabs of each hub member 6 preferably extend in an axial direction prior to assembly as indicated in FIGS. 4 and 5 so that they may easily be inserted through the slots 18 of the adjacent hub member 6 during assembly. Thereafter, they are bent radially outwardly against the radial flange 19 of said adjacent hub member and serve as means for interlocking said hub members as shown in FIGS. 1 and 2.

The size and shape of the tabs 21 and the associated slots 22 may vary considerably. Usually the tab is generally rectangular and is bent along the radially outer edge of the slot 22, which is preferably located at the outer cylindrical wall portion 26 of the channel 20. The length of the tab is preferably substantially the same as that of the slot 22 and is preferably at least half the radial width of the flange 19 and at least several times the

radial width of the slot 18, which is usually at least twice the thickness of the tab. The tab length should be less than the axial width of the channel 20 and is usually several times the tab width as shown in FIG. 5, for example.

The channel 20 of each hub member 6 has an inner sleeve portion 24 with an internal cylindrical surface that fits the external cylindrical surface of the shaft 2, a flat radial wall portion 25, and an outer tubular wall portion 26 with an external cylindrical surface which fits the inner cylindrical surface of the ring 5 (at wall 12). The inner sleeve portion and the radial wall portion are cut away to provide two key notches 23 of rectangular shape with a width substantially equal to the width of the key 9. The notches 23 of each hub member are diametrically opposed and located to fit on the keys 9 as shown in FIG. 1.

The outer tubular wall portion 26 of each hub member is provided with a series of regularly arranged rounded depressed key portions 27 located to receive the lobes 17 of the brush rings 5 (see FIGS. 1 and 3). The outer surface of the portions 27 may have generally the same shape and curvature as the radially inner surfaces of the lobes 17, but this is not necessary. The lobes 17 fit in the depressions at 27 to prevent relative angular movement between the brush ring 5 and the hub member 6 so that a considerable torque can be developed when required.

The construction of the hub members 6 is such that it is very easy to form the assembly B. For example, the assembly can be carried on very rapidly using a vertical press and a vertical shaft corresponding to shaft 2 with keys 9 as shown in FIGS. 1 and 2. One hub member 6 is placed on the vertical shaft with the tabs 21 extending upwardly. Then the ring 5 of a rotary brush 3 is moved axially over the tabs 21 and positioned on the outer surface of the wall portion 26 with the lobes 17 in the depressions 27. Another hub member 6 is then placed on the vertical shaft and moved downwardly until the radial flange 19 thereof engages the ring 5 with the slots 18 receiving the tabs 21. The tabs 21 are then bent radially outwardly against the flange 19 to secure the hub members together.

The assembly can be done quickly at extremely low cost. For example, all of the tabs 21 of one hub member can easily be bent down simultaneously by an annular tool carried by the vertical press in one or two pressing operations. After the tabs 21 have been bent to a radial position against the flange 19 of the last-mentioned hub member, the ring 5 of another brush section is lowered into place against the tabs 21, and another hub member is lowered onto the vertical shaft, and the cycle is repeated. The operations are repeated over and over again to provide a brush assembly B of the desired axial length which is commonly 15 to 25 inches or so but may be much greater.

The hub members 6 provide a strong rigid support for the brush sections and clamp the rings 5 in position. As shown, the difference between the axial distance between adjacent flanges 19 of the hub assembly 7 and the axial width of the brush ring 5 is equal to or slightly greater than the thickness of each tab 21 so that the tabs are clamped between and in engagement with the flanges 13 and 19, and it will be understood that such difference is preferably no more than 2 or 3 times the thickness of the tab so that the rings 5 are securely held against axial movement. It will also be understood that

axial movement of ring 5 may also be prevented by providing a tight or forced fit between ring 5 and the hub member. The assembly B may have an external diameter of 10 to 20 inches and an axial length of 6 inches to several feet. In the more common sizes, the hub member 6 has a wall portion 26 with an axial width of 0.4 to 0.7 inch and an external diameter of 4 to 8 inches, has 8 to 12 tabs (21) with a length 2 to 5 times its width, and has 3 to 5 regularly spaced depressed portions 27 of arcuate cross section with a maximum depth of 0.1 to 0.2 inch. However, the size and shape of the parts may vary considerably.

The hub assembly of the present invention is much less expensive than that of my U.S. Pat. No. 3,643,281 and requires fewer parts. Because of the ease of assembly and elimination of the need for spot welding or other reinforcing means, the cost of manufacture is reduced 20 to 25 percent or more.

The individual hub members 6 can be mass produced at low cost from flat sheet metal by a few simple stamping operations to shape the piece and to provide the various tabs and slots as will be readily apparent to those skilled in the art from the above disclosure.

The brush assembly B is well ventilated and permits ready flow of cooling air or fluid through the slots 22 and through the spaces between the radial flanges 19 of the hub members 6 and the flanges 13 of the brush rings 5.

It will be understood that in accordance with the patent laws, variations and modifications of the specific devices disclosed herein may be made without departing from the spirit of the present invention.

Having described my invention, I claim:

1. In a rotary brush assembly, an annular sheet metal hub member (6) comprising an annular channel (20) and an integral radial flange (19) with a large number of circumferentially spaced tab-receiving slots (18) therein located adjacent the outer tubular portion (26) of said channel, said channel having an inner shaft-engaging sleeve portion (24) and a radial wall portion (25) cut to provide a large number of vertically elongated slots (22) and integral elongated tabs (21) bent outwardly from said slots at the outer edges of said slots, each tab (21) being generally in axial alignment with one of said tab-receiving slots (18) and having a width less than the length of that slot, whereby the tabs of said hub member (6) will fit the tab-receiving slots of an identical hub member to provide means for interlocking said members.

2. The combination according to claim 1 wherein said outer wall portion (26) of said channel (20) has a series of rounded key portions (27) spaced around its circumference.

3. The combination according to claim 2 wherein said inner sleeve portion (24) and said radial wall portion (25) are cut away to provide at least one key notch (23).

4. The combination according to claim 3 wherein said channel (20) is drawn from a flat blank to provide said outer wall portion (26) with an axial width of 0.4 to 0.7 inch and a diameter of 4 to 8 inches.

5. The combination according to claim 4 wherein said hub member (6) has at least 8 tabs and each tab (21) has a length 2 to 5 times its width.

6. The combination according to claim 5 wherein said outer wall portion (26) has at least 3 regularly spaced key portions (27) and each key portion forms

a rounded generally cylindrical recess with a maximum depth of about 0.1 to 0.2 inch.

7. A hub assembly for a rotary brushing tool comprising a series of annular sheet metal hub members (6) adapted to be placed end to end in axial alignment, each hub member comprising an annular channel (20) and an integral radial flange (19) with a large number of circumferentially spaced tab-receiving slots (18) therein located adjacent the outer tubular portion (26) of said channel, said channel having an inner shaft-engaging sleeve portion (24) and a radial wall portion (25) cut to provide a large number of vertically elongated slots (22) and integral elongated tabs (21) bent outwardly from said slots at the outer edges of said slots, the tabs (21) of each hub member being adapted to extend through the tab-receiving slots (18) of an adjacent hub member (6) to provide means for interlocking said members.

8. A hub assembly according to claim 7 wherein the tabs (21) of each hub member (6) are bent radially outwardly against the radial flange (19) of an adjacent hub member.

9. A hub assembly according to claim 8 wherein the inner sleeve portion (24) and the radial wall portion (25) of each hub member (6) are cut away to provide at least one key notch (23) and wherein the key notches of all of the hub members (6) are in axial alignment.

10. A hub assembly according to claim 9 wherein the outer wall portion (26) of the channel (20) of each hub member (6) has a series of rounded indented key portions (27) spaced around its circumference, and wherein the key portions (27) of all of the hub members (6) are in axial alignment.

11. A rotary brush assembly comprising a series of generally circular rotary brushes (3), each having a channel-shaped annular hub ring (5) gripping the radially inner portions of radially extending bristles (4), a series of annular hub members (6) arranged end to end in axial alignment, each hub member comprising an annular channel (20) and an integral radial flange (19) with a large number of circumferentially spaced tab-receiving slots (18) therein located adjacent the outer tubular wall portion (26) of said channel, said channel having an inner shaft-engaging sleeve portion (24) and a radial wall portion (25) cut to provide a large number of vertically elongated slots (22) and integral elongated tabs (21) bent outwardly from said slots at the outer edges of said slots, the tabs (21) of one hub member ex-

tending through the tab-receiving slots (18) of an adjacent hub member and extending radially outwardly contiguous to the radial flange (19) of an adjacent hub member, the hub rings (5) of said brushes having a size to fit on the channels (20) of said hub members and being mounted thereon between the radial flanges (19) of said hub members.

12. A rotary brush assembly (B) according to claim 11 wherein the outer wall portion (26) of each channel (20) has a plurality of key portions (27) spaced around its circumference and the hub rings (5) are upset at circumferentially spaced locations to provide protruding lobes (17) that fit in said key portions to prevent relative angular movement between the hub ring (5) and the adjacent channel (20).

13. A rotary brush assembly according to claim 12 wherein one radial flange (13) of each hub ring engages the tabs (21) and the other radial flange (14) of that ring engages the radial flange (19) of an adjacent hub member, whereby the hub ring is held against axial movement.

14. A rotary brush assembly according to claim 13 wherein the tabs (21) of each hub member are sandwiched between and in engagement with the radial flange (19) of an adjacent hub member and the hub ring (5) of the rotary brush (3) carried by that hub member.

15. A rotary brush assembly according to claim 11 wherein the channels (20) of the hub member are cut away to provide axially aligned key-receiving notches (23).

16. A rotary brush assembly comprising a series of rotary brushes (3), each having a hub ring (5) and radial bristles (4), a series of annular hub members (6) arranged end to end in axial alignment, each hub member comprising a channel (20) and an integral radial flange (19) with circumferentially spaced tab-receiving slots (18) therein located adjacent the outer portion (26) of said channel, said channel having a wall portion (25) cut to provide elongated slots (22) and integral elongated tabs (21) bent outwardly from said slots, the tabs (21) of one hub member extending through the tab-receiving slots (18) of an adjacent hub member and engaging the radial flange (19) of an adjacent hub member, the hub rings (5) of said brushes being mounted between the radial flanges (19) of said hub members.
